(57) **CLAIM**

The ornamental design for a cord reel accessory, as shown and described.

DESCRIPTION

FIG. 1 is a top, rear, and left perspective view of a cord reel accessory, the cord on the cord reel accessory being shown in broken lines and therefore not constituting a part of the claimed design;

FIG. 2 is a front elevational view of the cord reel accessory of FIG. 1, the cord being shown in broken lines and therefore not constituting a part of the claimed design;

FIG. 3 is a rear elevational of the cord reel accessory of FIG. 1, the cord being shown in broken lines and therefore not constituting a part of the claimed design; and,

FIG. 4 is a right side elevational view of the cord reel accessory of FIG. 1, the left side elevational view being a mirror image thereof, the cord being shown in broken lines and therefore not constituting a part of the claimed design.
